[57] CLAIM

The ornamental design for a trash bag holder, as shown.

DESCRIPTION

FIG. 1 is a front elevational view of the bag holder according to my design;

FIG. 2 is a bottom view thereof;

FIG. 3 is a top view thereof;

FIG. 4 is a right side view of the bag holder of FIG. 1, the undisclosed left side view being a mirror image thereof;

FIG. 5 is a perspective view of the design of FIG. 1; and,

FIG. 6 is a perspective view of an alternate embodiment of

the bag holder illustrated in FIG. 5.
